UNITED STATES PATENT OFFICE.

DAVID D. WARD, OF AUSTIN, ILLINOIS, ASSIGNOR TO FREDERICK C. AUSTIN, OF CHICAGO, ILLINOIS.

MACHINE FOR DRILLING WELLS.

SPECIFICATION forming part of Letters Patent No. 617,894, dated January 17, 1899.

Application filed February 20, 1897. Serial No. 624,372. (No model.)

To all whom it may concern:

Be it known that I, DAVID D. WARD, a citizen of the United States, residing at Austin, in the county of Cook and State of Illinois, 5 have invented a certain new and useful Improvement in Machines for Drilling Wells and the Like, of which the following is a specification.

My invention relates more particularly to 10 machines for boring or drilling wells, but is also applicable to machines for performing analogous work for other purposes.

In a machine characterized by my invention the drill-rod or well-tube is rotated by a 15 gear-wheel having a centrally-arranged bore, through which the rod or tube is extended. The rod or tube is connected with the gear by a sliding or shifting connection, whereby the rod or tube may automatically descend 20 during the progress of the work. To provide for different sizes of rods or tubes without changing the gear, the bore of the gear is made polygonal and the rod or tube is provided with an adjustable sliding sleeve having 25 a polygonal exterior. In some cases the polygonal exterior of the sleeve fits the polygonal bore of the gear, while in other cases a bushing which is polygonal both internally and externally is removably fitted with- 30 in the bore of the gear and the externally-polygonal sleeve is fitted to slide within such bushing. The sleeve is adapted for temporary securement upon the rod or tube, whereby when necessary it can be adjusted thereon 35 from a lower to a higher position as the work progresses.

As a means for extracting the core after the bit has performed a suitable extent of work, I provide a tubular core-lifter containing one 40 or more springs, which, while preventing no material obstruction to the entrance of the core into the core-lifter, will automatically clutch the core when the core-lifter is raised.

In the accompanying drawings, Figure 1 45 illustrates the core-barrel and bit sunk in the ground. Fig. 2 is a like view with the bit removed and replaced by the core-lifter, which latter is in the act of receiving the core M. In Fig. 1 the devices for operating and 50 holding the drill-rod are shown, while in Fig.

2 such devices are omitted. Fig. 3 is a longitudinal central section, on a larger scale, through the core-barrel and core-lifter, the former being broken away for convenience of illustration. Fig. 4 shows the devices for 55 operating and holding the drill-rod in elevation. Fig. 5 is a section on line x x in Fig. 4. Fig. 6 is a longitudinal section, on a smaller scale, through the core-barrel and core-lifter, having a modified form of spring. Fig. 7 is 60 a section through one of the bevel-gears and a modified form of sleeve for engaging the drill-rod. Fig. 8 shows in elevation the lower end portion of the sleeve F of Fig. 7. Fig. 9 is a section on line y y in Fig. 7. Fig. 10 is 65 a section on line z z in Fig. 6.

The mechanism for rotating the drill comprises a couple of intermeshing bevel-gears A and B, the former of which is fixed upon a rotary power-driven shaft C, understood to be 70 connected with and operated by any suitable engine. The gear B is supported by a bracket D, arranged to swing about the axis of shaft C and constructed with a swinging bearing for the hub b of the gear B. One part d of this 75 bracket is hinged to the other part d', as at d', whereby the part d can be swung outward when it becomes desirable to remove the gear B. When said parts of the bracket are closed together, they can be locked the one to the other by a bolt E.

The gear B is provided with a polygonal bore b', which extends axially through the gear and the hub portion thereof, an illustration 80 of a polygonal bore through the gear being 85 afforded by Figs. 5 and 9.

A sleeve F, having a cylindric bore and made externally polygonal in correspondence with the polygonal bore of the gear B, is fitted to slide up and down within said bore of gear 90 B. This sleeve is fitted to slide upon the well-tube or drill-rod, as the case may be, it being usual, however, to adapt it to receive and fit upon a drill-rod G, which may be solid or hollow, but preferably the latter.

In Fig. 4 the sleeve F is temporarily secured 95 upon the drill-rod by one or more set-screws f, while in Fig. 7 the lower end of the sleeve is understood to be externally threaded and provided with splits f', as in Fig. 8, and to have 100

its split end clamped upon the drill-rod by a nut H , screwed upon the externally-threaded end portion f^2 of the sleeve. Where the rod G and sleeve F are comparatively large, one or more set-screws can be advantageously employed, since in such case the sleeve will afford suitable bearings for the set-screws; but where the rod and sleeve are comparatively small and the sleeve is made of comparatively thin material it may be more advantageous to split and thread one end of the sleeve and employ a tightening-nut, as in Fig. 7.

In Figs. 4 and 5 the polygonal sleeve fits the polygonal bore of the gear B ; but where a smaller rod is employed I fit within the bore of the gear B a bushing I , which is externally and internally polygonal in conformity with the bore of the gear and which is provided at one end with a stop or shoulder i , which rests upon the middle plane portion of the gear, as in Fig. 7, so as to prevent the bushing from dropping down through the gear. This bushing is internally fitted to the reduced sleeve F , Figs. 7 and 9, and the said sleeve is fitted to the reduced drill-rod G . By employing bushings I of various dimensions various sizes of drill rods or tubes can be readily and conveniently employed without changing the gear, and it will also be observed that the bushing I and the gear B are adapted to be readily removed and replaced without the use of tools—that is to say, after swinging the bearing outwardly the bushing and the gear may be raised therefrom and replaced by hand, as the said bushing and gear are constructed without flanges, bolts, screws, or other devices which would necessitate the use of screw-drivers, wrenches, &c.

During the operation of drilling the drill-rod and the sleeve F secured thereon automatically slide downwardly through the gear B , according to the progress of the work. When, however, the sleeve reaches the limit of its allotted drop, (which can be determined by a stop or shoulder f^3 upon the upper end of the sleeve coming in contact with the gear B), the device for fastening the sleeve upon the drill rod or tube can be released and the sleeve can be shifted upwardly upon the rod or tube and again fastened thereon. In this way, therefore, while the sleeve and rod will automatically drop during the progress of the work the sleeve can from time to time be adjusted from a lower to a higher position upon the drill-rod, according to requirements.

In Fig. 1 the drill-rod is detachably secured to the upper end of a core-barrel K , and a tubular bit L is detachably secured to the lower end of the core-barrel. During the process of drilling, particularly through rock, a core will be formed, as in Fig. 2, wherein such a core is indicated by letter M and shown partly exposed and partly within the core-barrel, as represented by dotted lines. After such a core has been formed the drill-rod, core-barrel, and bit can be raised and the bit removed and replaced by a core-lifter N . The

rod, barrel, and core-lifter can then be sunk, as in Fig. 2, in which the core-lifter is understood to be passing downwardly over the core, which is to be subsequently raised by again raising the barrel to which the core-lifter is attached.

The core-lifter N consists of a comparatively short barrel adapted to couple with the core-barrel K by a threaded or other suitable joint or coupling and provided with one or more internally-arranged springs, which are normally deflected toward the axial center of the core-lifter. In Fig. 3 the shank portions p of springs P are secured to the inner wall of the core-lifter, and the free portions of said springs are normally deflected toward the center. The inner wall of the core-lifter is recessed, as at n , whereby when the core-lifter is passing down over a core the latter can force the springs back into position flush with the inner cylindric wall of the core-lifter, and hence no obstruction will be offered to the reception of the core within the core-lifter and core-barrel. Upon raising the core-barrel and core-lifter, however, the upper ends of the springs will engage and clutch the core, so as to cause the latter to break away at its base and to rise with the ascending core-barrel and core-lifter. Other forms of spring or springs having like action may also be employed. Thus the spring can be a longitudinally-split sleeve R , of trunco-conical shape, secured to the inner wall of the core-lifter by an arm r , as in Figs. 6 and 10.

As a preferred mode of operation the bit attached directly to the core-barrel is first employed, and subsequently the bit is detached and replaced by the core-lifter, as hereinbefore described; but I can, however, in the first instance attach the core-lifter to the core-barrel and attach the bit to the core-lifter, in which case one end of the core-lifter will be adapted for connection with the core-barrel, while its opposite end will be adapted for connection with the bit. I can also arrange one or more of the aforesaid clutch-springs within the tubular bit in place of within a core-lifter n and dispense with the latter, in which case the bit will act as a core-lifter, or I can employ the core-lifter and bit and arrange the springs in both. I prefer, however, to provide a detachable core-lifter having one or more clutch-springs, as hereinbefore set forth, and to dispense with springs in the bit.

I claim—

In a rotary core-drill for drilling wells or the like, a gear B having a polygonal bore and a hub b ; a bushing I externally and internally polygonal and removably fitted within the polygonal bore of the gear, said bushing being provided with a stop which rests upon the gear so as to support the bushing therein; an externally-polygonal sleeve fitted to slide within the polygonal bushing and having a stop arranged to limit its downward movement; a drill rod or tube fitted to slide with-

in the sleeve, and a fastening device by which
the sleeve can be secured in adjustment upon
the drill-rod, the foregoing construction and
arrangement being adapted to permit the use
5 of different sizes of drill rods or tubes with-
out changing the gear, and also to permit easy
removal and replacement of the gear and

bushing without the use of tools; substan-
tially as described.

DAVID D. WARD.
